UNITED STATES PATENT OFFICE

RICHARD C. WOLFE, OF BEVERLY HILLS, CALIFORNIA

REFRIGERATOR

Application filed August 4, 1930. Serial No. 472,855.

This invention relates to refrigerators and more particularly to a refrigerating machine, device or apparatus which performs the cooling function by drawing an expansible liquid through a porous, permeable cellular or vesicular membrane or medium by the reduction of the pressure on one side of the medium so that the expansible liquid is expanded or evaporated, the heat of vaporization of the liquid being drawn from the surroundings to reduce the temperature thereof.

The principal object of my invention is to provide an inexpensive form of refrigerating apparatus for use in reducing the temperature of a chamber of liquid or other substance to a temperature immediately above freezing, or to approximately 32° F., employing a vacuum refrigerating machine in which a porous or permeable membrane is used in place of the customary expansion valve.

Another object of my invention is to provide a refrigerating device using as the refrigerant a substance which is liquid during one part of the cycle of the operation and gaseous at another part of the cycle of operation, the liquid being caused by a differential pressure to permeate a porous membrane in passing to the side of the membrane at low pressure and the liquid when passing into the zone of low pressure being vaporized so that the heat required for the vaporization of the liquid is drawn from the remaining fluid contained within the permeable or porous membrane to reduce the temperature thereof to approximately 32° F.

Another object of my invention is to provide an inexpensive form of water cooler for reducing the temperature of drinking or like water in which the water acts as the refrigerant and is forced to pass through a porous or permeable membrane by the reduction of the pressure upon one side of the membrane, the water remaining at, or substantially at, atmospheric pressure on the opposite side of the membrane so that the water on passing into the zone of reduced pressure is evaporated to reduce the temperature of the water in the container and the rate of evaporation of the water being regulated to control the

degree of temperature to which the water in the container is reduced.

Other objects and advantages of this invention it is believed will be apparent from the following detailed description of a preferred embodiment thereof as illustrated in the accompanying drawing.

In the drawing:

Figure 1 is a side elevation of an apparatus embodying this invention illustrating a water cooler as connected with a vacuum pump driven by a motor and including an adjustable thermostatic control for controlling the operation of said motor in relation to the temperature of the water in the cooler.

Figure 2 is a fragmental sectional elevation substantially in mid-vertical section of a refrigerator embodying my invention.

In the preferred embodiment of my invention illustrated in the accompanying drawing, 1 indicates a container preferably formed of porcelain or stone-ware which is glazed upon its exterior surface 2. Formed on the under surface of the container 1 is an upwardly extending annular flange 3, while formed at the upper end of the container 1 is an inwardly turned annular flange 4.

Mounted within the container 1 and held spaced therefrom by means of the flanges 3 and 4 is a secondary stone-ware or porcelain container 5 which has its inner periphery 6 glazed. Positioned between the containers 1 and 5 as indicated at 7 is an insulating material to prevent the passage of heat from the exterior of the container 1 into the interior of the container 5. An outlet passage 8 is formed through the containers 1 and 5 and is fitted with a bushing 9 into which a suitable valve, faucet or the like 10 is provided for drawing water from within the interior of the container 5.

Formed integral with the container 1 is a bell or dome 11 which extends into the interior of the container 5 and is formed unglazed on each side so as to provide a porous or permeable membrane through which water from within the container 5 may pass as the pressure within the zone 12 of reduced pressure is reduced. Extending into the dome 11

is a conduit 13 which is closed at its upper end by means of a cap 14 which is secured to the end of the conduit 13 and is packed by a packing 15 to provide a fluid tight joint. The conduit 13 is formed integral with a base plate 40 and is connected by means of a connection 18 with a conduit which leads to a vacuum pump 19. The vacuum pump 19 may be driven by any suitable or desirable form of means such, for example, as the electric motor indicated at 20.

The base plate 40 fits within the flange 3 of the container 1 and is packed against the lower end of the dome 11 by means of a packing ring 16. A cap 17 fits within the flange 3 to engage the base plate 40 and the assembly 15 is secured in position by means of a nut 41^a screw-threaded to the lower end of the conduit 13.

20 The electric motor may be controlled in operation by means of a thermostat 21 mounted within the interior of the chamber 5 and connected with the electric motor so as to control the operation of the motor 20 in accordance with the temperature of the water within the container 5.

When the refrigerator is used for the purpose of cooling water, it is not desirable to reduce the temperature of the water below 30 40°. However, when the refrigerator embodying my invention is used for the purpose of providing a refrigerant for cooling other substances, it is desirable to reduce the temperature of the refrigerant to approximately 35 32° F.

The container 5 is provided at its upper end with an outwardly extending flange 22 which fits over the flange 4 above the level of the water within the container 5, the level of 40 water being indicated at 23.

A cover member 24 is provided which is likewise formed of porcelain or earthenware and is cast to provide an open chamber 25 in which insulating material 26 is positioned. 45 The cover 24 is provided with a downwardly extending annular flange 24^a which fits over the edge of the flange 22 of the inner container 5 and engages the upper edge of the container 1. The cover member 24 is preferably glazed on all of its exterior surfaces.

Means are provided for controlling the flow of water into the container 5 to prevent flow of heat from the water contained in the inverted water bottle 27 into the water 55 contained within the container 5. Means for preventing the flow of heat from the water in the water bottle 27 to the water within the container 5 may be of any desired construction and is herein illustrated as including a float valve 28 which is mounted within the passage 29 formed through the cover member 24. The float valve 28 is retained in position by means of a stop bar 30 which is extended across the passage 29. The cover 60 65 is formed with a bell-shaped passage so that

it provides a seat 31 upon which the float valve 28 seats to prevent circulation of water from the water bottle 27 to the water within the container 5 when the water within the container 5 is of a high enough level to hold the float valve 28 on its seat. By this means the water within the container 5 may be retained at a low temperature and the heat exchange between the water in the bottle 27 and the water within the container 5 is prevented. The float valve 28 is preferably formed as a ball having the air withdrawn from its inner periphery to produce a partial vacuum within the ball. The vacuum float ball 28 thus produced provides an insulated float valve retarding the flow of heat between the water contained in the bottle 27 and the container 5.

The water bottle 27 fits in the cover member 25 in the opening 32 so that its spout 33 is held elevated from the float valve 28. The particular illustration of the refrigerator herein given is a water cooler, but it is obvious that my invention is not limited to the cooling of water but that the principle of my invention may be employed for refrigerating any desired substance and is particularly applicable for domestic refrigerators and the like wherein water or a like liquid is available for the purpose of providing the refrigerant to be used.

The refrigerator embodying my invention as herein illustrated has the following mode of operation:

The water bottle 27 is positioned upon the cover member 24 so that water flows from the bottle 27 to fill the container 5. As soon as the water raises in the container 5 to a sufficient level, the float valve 28 is forced against the seat 31 to limit the exchange of heat between the water of the container 5 and the water of the bottle 27. The motor 20 is set in operation and the vacuum pump operates to reduce the pressure within the dome 11 drawing the air or vapor within the dome 11 through the ports 34. The pressure of the water within the container 5 is atmospheric. The pressure within the dome 11 will be reduced several inches of mercury below atmospheric pressure so that the water within the container 5 flows through the permeable or porous membrane provided by the porcelain or stone-ware of which the dome 11 is formed, and as the water enters the zone 12 of reduced pressure it vaporizes and as it is vaporized, it draws its heat of vaporization from these surroundings. The heat of vaporization is thereby provided by the water within the container 5 as the water is insulated by the insulation 7 and 26. The drawing of the heat of vaporization from the water within the container 5 reduces the temperature of the container 5 to the point where the thermostat is set to stop the operation of the motor 20 and hence the vacuum pump 19.

As soon as the temperature of the water within the container 5 raises, the thermostat 21 will again open the circuit to the electric motor 20 and the vacuum pump 19 will be set 5 to again reduce the pressure within the dome 11 causing further water to permeate the permeable membrane 11 to be vaporized and again reduce the temperature of the water in the container 5.

10 Having fully described my invention, it is to be understood that I do not wish to be limited to the details herein set forth, but my invention is of the full scope of the appended claims.

15 I claim:

1. In a refrigerator including a chamber to receive the substance to be cooled, a pervious membrane, a refrigerant at atmospheric pressure on one side of the membrane, and 20 means for reducing the pressure on the opposite side of said membrane so that the refrigerant is forced through the pervious membrane.

2. In a water cooler, the combination of a 25 container adapted to receive water, a pervious membrane projecting into said container, and means for reducing the pressure within said membrane so that water penetrates therethrough and is evaporated, the heat of vaporization being extracted from the water remaining in said container to reduce the temperature thereof.

3. In a refrigerator including a chamber 30 adapted to receive a liquid refrigerant, a pervious membrane connected with the chamber, means for reducing the pressure on one side of said membrane so that the liquid refrigerant is forced therethrough into a zone of reduced pressure and is evaporated, the heat of vaporization of said liquid being extracted from the remaining liquid in said chamber to reduce the temperature thereof.

4. In a water cooler, the combination of a 35 container adapted to receive water, means for insulating the container, a pervious membrane connected with the chamber, means for reducing the pressure on the side of said membrane exterior to said container so that the water penetrates therethrough and is evaporated, the heat of vaporization of said water being extracted from the remaining water in said container to reduce the temperature thereof.

5. In a water cooler, the combination of a 40 container adapted to receive water, means for insulating the container, a pervious membrane connected with the container, a cover for the container, means for insulating the cover, means for reducing the pressure on the side of said membrane exterior to the said container so that the water penetrates therethrough and is evaporated, the heat of vaporization being extracted from the remaining water in said container to reduce the temperature thereof.

6. In a water cooler, the combination of a container adapted to receive water, a pervious membrane projecting into said container, means for reducing the pressure within said membrane, and means for producing a difference 70 and is evaporated, means for controlling the degree of pressure reduction within said membrane to control the rate of vaporization of said water to control the temperature reduction of the water in said container, the heat of vaporization of the water passing through said membrane and being evaporated in the zone of reduced pressure being extracted from the water remaining in 75 said container.

7. In a refrigerator including a chamber to receive the substance to be cooled, a pervious membrane, a refrigerant of atmospheric pressure on one side of the membrane, means for reducing the pressure on the opposite side 80 of the membrane, means for controlling the degree of pressure reduction on said side of the container, and the refrigerant being forced through the pervious membrane by the pressure differential on the opposite sides 85 thereof so that the refrigerant on passing into the zone of reduced pressure is evaporated, and the heat of vaporization being taken from the remaining refrigerant in said chamber.

8. In a water cooler, the combination of a container adapted to receive water, a pervious membrane projecting into said container, a cover for said container, means mounted on the said cover for maintaining water in the 100 container to a predetermined volume, means for reducing the pressure within said membrane so that water penetrates thereto and is evaporated, the heat of vaporization being extracted from the water remaining in said 105 container to reduce the temperature thereof, and means for preventing water circulation between the water in said container and the water supply means.

9. In a water cooler, the combination of a 110 container adapted to receive water, means for reducing the temperature of the water within the container, a water supply container inverted over the first said container to supply water thereto, and means interposed between 115 the first said container and the second said container to limit the heat transfer by conduction between the waters carried in said containers.

10. In a water cooler, the combination of 120 a container adapted to receive water, a water bottle inverted on the top of said container and having its neck projecting into said container for maintaining water in the container 125 to a predetermined volume, and valve means for retarding the conductive transfer of heat from the water in said inverted bottle to the water in the said container.

11. In a refrigerator including a chamber 130

4

to receive substance to be cooled, a pervious membrane, a refrigerant on one side of said membrane, and means for reducing a differential pressure upon opposite sides of said membrane so that the refrigerant is forced through the pervious membrane.

12. In a refrigerator, the combination of a container including a liquid to be cooled, a second container inverted at the top of the first container for maintaining the liquid in the first said container to a predetermined level, and a vacuum float valve between the said containers for arresting the flow of liquid from the second said container to the first said container when the liquid in the first said container reaches a predetermined level, and for retarding the transfer of heat from the liquid in the second said container to the first said container.

20. Signed at Los Angeles, Calif. this 29th day of July, 1930.
